UNITED STATES PATENT OFFICE.

FRANK C. ANDERSON, OF CINCINNATI, OHIO, ASSIGNOR TO THE AMERICAN VALVE AND METER COMPANY, OF CINCINNATI, OHIO, A CORPORATION OF OHIO.

AUTOMATIC SAFETY SWITCH-LOCK.

1,234,522.

Specification of Letters Patent.

Patented July 24, 1917.

Application filed September 11, 1916. Serial No. 119,474.

To all whom it may concern:

Be it known that I, FRANK C. ANDERSON, a citizen of the United States, residing at Cincinnati, in the county of Hamilton and State of Ohio, have invented certain new and useful Improvements in Automatic Safety Switch-Locks, of which the following is a specification.

My invention relates to means to be used 10 in connection with a switch stand for automatically locking the switch points of a railway independently of the switchstand. The objects of my invention are to provide simple, economical, convenient and effective means of the above character in connection with a switch stand of the weighted ground lever automatic type, and to prevent the locking of said switch stand unless the switch is properly closed, as well as to provide 15 convenient means to unlock the switch points to open the switch; to provide such a device which will always hold the switch points in locked position even though the switch stand should become disconnected, 20 damaged or destroyed by accident under traffic; to provide means in connection with certain forms of switch stands to insure the proper closing of the switch points against the stock rails before the switch can be 25 locked in closed position; and to provide a device of the above character which can be readily applied.

My invention consists in the combination of parts and in the details of construction 30 and arrangement of parts as will hereinafter be more fully described and claimed.

In the drawing:

Figure 1 is a general perspective view of 40 a switch and switch stand with which my invention is associated;

Fig. 2 is a plan view of the lock and showing part of the switch stand latch treadle;

Fig. 3 is a side elevation of the same, and 45 showing only part of the latch of the switch stand;

Fig. 4 is a vertical cross section of the same on a plane corresponding to the line 4—4 of Fig. 3;

50 Fig. 5 is a detail perspective view of the bell-crank; and

Fig. 6 is a similar view of the rack.

Constructed as illustrated, the switch stand 1, of the weighted ground lever type, 55 is suitably mounted upon head-blocks or

ties 2 and connected to the switch points 3 by a connecting rod 4. The operating lever 5 of the switch stand is held down by the keeper 6 of the latch in the usual manner when the switch is in closed position. This 60 keeper has a treadle 7 which is engaged by the foot of the operator, after the latch has been unlocked, to draw the keeper back and release the operating lever.

My automatic safety switch-lock which is 65 used in connection with the above described mechanism comprises a mounting or housing 8 on the upper side of and integral with a plate 9 near one end thereof. On the lower side of this plate 9, near the other end 70 thereof and integral therewith, is the interlocking-bar guide 10 for the interlocking bar 11, which latter is of rectangular cross section, with its narrower sides presented upwardly and downwardly, and which fits 75 snugly in and slides through a slot 12 of corresponding shape, in said guide 10. The interlocking plunger 13 is also guided in this guide 10 at right angles to the guiding of the interlocking bar 11, and passing through 80 an opening 14 in said bar when the bar is in position to have this opening 14 registering with alined openings 15 and 16, in which the plunger 13 is guided in the guide 10 at opposite sides of the slot 12. This plunger 85 is preferably of circular cross section as are also the opening 14, 15 and 16, in all of which said plunger 13 fits and slides snugly. Near its other end, on its lower side and integral with it, the plate 9 has the plunger 90 guide 17 extending downwardly with an opening 18 to receive the other end part of the plunger 13, which extends longitudinally of the structure.

The rack 19 comprises a horizontal part 20 95 with a downwardly extending part 21 through which passes the plunger 13, and by means of which said rack is attached to said plunger by a pin 22 passing transversely through the part 21 and through the 100 plunger, and removably held in place by a cotter pin 23. This rack is attached to the plunger 13 in such a position that the part 21 will abut the inner side of the guide 10 when the plunger 13 is extended entirely 105 through the guide 10 and the interlocking bar 11, with the horizontal part 20 extending over toward the end of the structure. On this other end of the horizontal part 20 is an engaging head 24 with a vertical slot 25 110

through it; and on the top of the horizontal part 20, between the slot 25 and the downwardly extending part 21, is a neck 26 extending up through a slot 27 in the bottom 28 of the housing 8, and having lateral ears 29 extending over the upper side of the bottom 28 along opposite edges of the slot 27. A helical spring 30 surrounds the plunger 13 between the plunger guide 17 and the 10 downwardly extending part 21 of the rack 19, and preferably has washers 31 interposed between its ends and the parts 17 and 21. This spring thus forces the plunger to project through and retentively engage with 15 the interlocking bar 11 when the opening 14 registers with the openings 15 and 16; and when the plunger 13 is withdrawn, and the interlocking bar moved so as to bring this opening 14 out of register with the openings 20 15 and 16, this spring 30 holds the plunger 13 against the side of the interlocking bar 11 ready to enter the opening 14 the instant 25 that it comes again into proper registering position. The ears 29, bearing along the sides of the slot 27 in the bottom 28 of the housing, serve to support the overhanging end of the rack 19 with its engaging head 24.

The bell-crank 32 comprises the transverse shaft 33, which has a journal bearing 34 in 30 the top of the housing 8 and held down in this bearing 34 by a cap 35 fixed to the top of the housing by cap screws 36; and also comprises an arm 37 extending downwardly from its middle and having its lower end 35 part in the slot 25 to detachably engage with the inner side of the end of said engaging head; and also comprises the arms 38 on said shaft 33 outside the housing 8 at opposite sides thereof, and extending over 40 toward the end that has the interlocking-bar guide 10, and having on their end parts the treadles 39 extending out in opposite directions from the housing 8. This shaft 33 and the arms 37 and 38 and the treadles 45 39 are preferably integral.

My improved automatic safety switch-lock, constructed substantially as above described, is installed by cutting, transversely in the top of the head-block or tie 2 that 50 supports the latch in which the switch is locked in closed position, a recess or gain 40 from one side of this head-block 2 to the other; and fastening the plate 9 down on this head-block 2, preferably by means of 55 lag-screws 41, with the inner side part of the interlocking-bar guide 10 and the plunger guide 17 projecting down into this gain 40. Thus the rack 19 and spring 30 and associated parts are inclosed inside the 60 head-block 2; the parts that extend down from the plate 9 preferably being nearly as wide as the gain 40 so as to practically close the ends of the gain 40, and the guide 10 also preferably having a flange 42 around its vertical sides and bottom to closely abut the 65

side of the cross tie around the adjacent end of the gain 40.

This gain 40 is so located in the head-block relative to the latch that one of the treadles 39 will lie over the treadle 7 of 70 the latch in such proximity thereto that, when the treadle 39 and arm 38 are depressed to withdraw the plunger 13 from the interlocking bar 11 against the pressure of the spring 30, the treadle 7 will also be 75 depressed and will withdraw the keeper 6 of the latch so as to permit the raising of the operating lever 5 of the switch stand and the throwing of the switch; which is permitted also by the withdrawal of the 80 plunger 13 from the interlocking bar 11, which is connected to one of the switch points 3, as shown in Fig. 1.

If the switch turns out in the opposite direction, necessitating its being locked in 85 the latch on the other head-block, and location of the interlocking bar 11 along the other side of the other head-block, my automatic safety switch-lock is placed in reversed position on said other head-block. Then 90 the other arm 38 and treadle 39 become operative instead of the ones that operate on this side. In either instance the opposite treadle 39 lies outside, completely accessible to the operator's foot. It is for these 95 reasons that I provide the bell-crank with the two opposite arms 38 and treadles 39. Also, the arms 38 and treadles 39 preferably lie below the top of the housing 8, and are thus amply guarded against accidental depression.

Preferably, the plunger 13 has its part that passes through the part 21 of the rack 19 reduced in diameter so that a shoulder 105 43 is formed between this part and the part that slides in the guide 10, and against which shoulder the rack 19 abuts, as held by the pin 22. This entire lower mechanism is readily disassembled, when the switch-lock is removed from the head-block, by removing the cotter pin 23 and withdrawing the pin 22, which allows the plunger 13 to be withdrawn through the guide 10, and allows the spring 30 and its washers 31 to drop out from between the guide 10 and plunger guide 17. The upper mechanism comprising the bell-crank 32 and rack 19, are readily removed by merely removing the cap screws 36 and taking off the cap 35.

By having the plunger 13 that engages with the interlocking bar 11 entirely below the upper side of the head-block 2, and having detachable operative connection between it and the bell-crank 38, there is little liability of displacement of this plunger from 120 its operative position in holding the interlocking bar, whatever accident may befall the switch stand and mechanism of my automatic safety switch-lock above the top of the head-block. Thus, although this entire 125 130

upper mechanism be dislocated or destroyed, the interlocking bar 11 will still be held by the plunger 13 and prevent the switch points 3 from moving, thereby maintaining the 5 switch in safe position regardless of the accident which may have destroyed the switch stand, and would therefore, otherwise have left the switch points 3 without any means to hold them in safe position. The plate 9, 10 being rigidly secured to the head-block, will maintain its position with the plunger 13 held in proper position therein under the most severe conditions.

An important advantage attained by the 15 use of this type of locking mechanism is the prevention of the locking of the switch with an obstruction between the switch point and stock rail which would be small enough to permit the negligent operator to spring the 20 parts sufficiently to bring the operating lever 5 down into the latch and lock it, although this obstruction would be large enough to hold the switch point away and cause derailment. Likewise this lock prevents the 25 locking of the switch stand with the switch point left away from the stock rail due to wear or disconnection of the operative connection between the switch points and the switch stand mechanism. In either continuity, 30 as the interlocking bar 11 is moved by the switch points, it will not move up far enough to allow the plunger 13 to enter the opening 14 unless these switch points actually move up to safe position against the 35 stock rails. Unless this plunger 13 can enter the opening 14, the lock can not be inserted in the eye of the latch, because the keeper 6 is held out thereover, as seen in Fig. 3. The device herein illustrated provides for this 40 inexpensively, due to the simplicity and comparative smallness of the parts used, thereby saving in labor and construction as well as material; and is also more easily installed, as has been above pointed out.

45 It will be understood that the invention is capable of some modification from the construction specifically illustrated and described herein without departure from the scope and spirit of the invention, which is 50 defined by the following claims:

1. An automatic safety switch-lock comprising an interlocking bar, and means to lie below the top of the head-block and retentively engage with said interlocking bar, and 55 means having operative connection with said retentively engaging means to withdraw it from its engagement with said interlocking bar, and comprising engaging means adapted to engage with a part of the latch of a switch stand, and thereby hold said latch out of position for locking while said retentively engaging means is withdrawn from said engagement.

2. An automatic safety switch-lock comprising an interlocking bar, and means to lie 60

below the top of the head-block with said means in a recess in the head-block and retentively engaging with said interlocking bar, and means having operative connection with said retentively engaging means to withdraw it from its engagement with said interlocking bar, and comprising engaging means adapted to engage with a part of the latch of a switch stand, and thereby hold said latch out of position for locking while 75 said retentively engaging means is withdrawn from said engagement.

3. An automatic safety switch-lock comprising a mounting, an interlocking bar, and means to lie in said mounting below the top 80 of the head-block and retentively engage with said interlocking bar, and means extending through said mounting and having operative connection with said retentively engaging means to withdraw it from its engagement with said interlocking bar, and comprising engaging means lying below the 85 top of said mounting, adapted to engage with a part of the latch of a switch stand, and thereby hold said latch out of position 90 for locking while said retentively engaging means is withdrawn from said engagement.

4. An automatic safety switch-lock comprising an interlocking bar, and means to lie below the top of the head-block and retentively engage with said interlocking bar, and means having operative connection with said retentively engaging means to withdraw it from its engagement with said interlocking bar, and comprising oppositely presented engaging means, one or the other of said engaging means being adapted to engage with a part of one or the other latch of a switch stand, accordingly as said switch-lock is associated with one or the other of 100 said latches, and being thereby adapted to hold said latch out of position for locking while said retentively engaging means is withdrawn from said engagement.

5. An automatic safety switch-lock comprising an interlocking bar, and means to lie below the top of the head-block, and retentively engaging with said interlocking bar, and means extending through said mounting and having detachable operative 115 connection with said retentively engaging means to withdraw it from its engagement with said interlocking bar, and comprising engaging means adapted to engage with a part of the latch of a switch stand, and thereby hold said latch out of position for locking while said retentively engaging means is withdrawn from said engagement.

6. An automatic safety switch-lock comprising a mounting, an interlocking bar, and means to lie in said mounting below the top 120 of the head-block and retentively engage with said interlocking bar, and means extending through said mounting and having detachable operative connection with said 125

130

retentively engaging means to withdraw it from its engagement with said interlocking bar, and comprising engaging means lying below the top of said mounting, adapted to engage with a part of the latch of a switch stand, and thereby hold said latch out of position for locking while said retentively engaging means is withdrawn from said engagement.

10 7. An automatic safety switch-lock comprising a mounting, an interlocking bar, and means to lie in said mounting below the top of the head-block with said means in a recess in the head-block, and retentively engaging 15 with said interlocking bar, and means extending through said mounting and having operative connection with said retentively engaging means to withdraw it from its engagement with said interlocking bar, 20 and comprising engaging means lying below the top of said mounting, adapted to engage with a part of the latch of a switch stand, and thereby hold said latch out of position for locking while said retentively 25 engaging means is withdrawn from said engagement.

8. An automatic safety switch-lock comprising an interlocking bar, and means to lie below the top of the head-block and re-
30 tentively engage with said interlocking bar, and means having detachable operative connection with said retentively engaging means to withdraw it from its engagement with said interlocking bar, and comprising
35 oppositely presented engaging means, one or the other of said engaging means being adapted to engage with a part of one or the other latch of a switch stand, accordingly as said switch-lock is associated with
40 one or the other of said latches, and being thereby adapted to hold said latch out of position for locking while said retentively engaging means is withdrawn from said engagement.

45 9. An automatic safety switch-lock comprising an interlocking bar, and means to lie below the top of the head-block with said means in a recess in the head-block, and retentively engaging with said interlocking bar, and means having operative connection with said retentively engaging means to withdraw it from its engagement with said interlocking bar, and comprising oppositely presented engaging means, one or the other 50 of said engaging means being adapted to engage with a part of one or the other latch of a switch stand, accordingly as said switch-lock is associated with one or the other of said latches, and being thereby 55 adapted to hold said latch out of position for locking while said retentively engaging means is withdrawn from said engagement. 60

means to lie in said mounting below the top

of the head-block and retentively engage with said interlocking bar, and means extending through said mounting and having operative connection with said retentively engaging means to withdraw it from its engagement with said interlocking bar, and comprising oppositely presented engaging means lying below the top of said mounting, one or the other of said engaging means being adapted to engage with a part of one or the other latch of a switch stand, accordingly as said switch-lock is associated with one or the other of said latches, and being thereby adapted to hold said latch out of position for locking while said retentively engaging means is withdrawn from said engagement. 70 75 80

11. An automatic safety switch-lock comprising a mounting, an interlocking bar, and means to lie in said mounting below the top of the head-block with said means in a recess in the head-block, and retentively engaging with said interlocking bar, and means extending through said mounting and having detachable operative connection with said retentively engaging means to withdraw it from its engagement with said interlocking bar, and comprising engaging means lying below the top of said mounting, adapted to engage with a part of the latch of a switch stand, and thereby hold said latch out of position for locking while said retentively engaging means is withdrawn from said engagement. 85 90 95

12. An automatic safety switch-lock comprising an interlocking bar, and means to lie below the top of the head-block with said means in a recess in the head-block, and retentively engaging with said interlocking bar, and means having detachable operative connection with said retentively engaging means to withdraw it from its engagement with said interlocking bar, and comprising oppositely presented engaging means, one or the other of said engaging means being adapted to engage with a part of one or the other latch of a switch stand, accordingly as said switch-lock is associated with one or the other of said latches, and being thereby adapted to hold said latch out of position for locking while said retentively engaging means is withdrawn from said engagement. 100
105
110
115

13. An automatic safety switch-lock comprising a mounting, an interlocking bar, and means to lie in said mounting below the top 120 of the head-block and retentively engage with said interlocking bar, and means extending through said mounting and having detachable operative connection with said retentively engaging means to withdraw it 125 from its engagement with said interlocking bar, and comprising oppositely presented engaging means lying below the top of said mounting, one or the other of said engaging means being adapted to engage with a part 130

of one or the other latch of a switch stand, accordingly as said switch-lock is associated with one or the other of said latches, and being thereby adapted to hold said latch out 5 of position for locking while said retentively engaging means is withdrawn from said engagement.

14. An automatic safety switch-lock comprising a mounting, an interlocking bar, and 10 means to lie in said mounting below the top of the head-block with said means in a recess in the head-block, and retentively engaging with said interlocking bar, and means extending through said mounting and 15 having operative connection with said retentively engaging means to withdraw it from its engagement with said interlocking bar, and comprising oppositely presented engaging means lying below the top of said 20 mounting, one or the other of said engaging means being adapted to engage with a part of one or the other latch of a switch stand, accordingly as said switch-lock is associated with one or the other of said 25 latches, and being thereby adapted to hold said latch out of position for locking while said retentively engaging means is withdrawn from said engagement.

15. An automatic safety switch-lock comprising a mounting, an interlocking bar, and 30 means to lie in said mounting below the top of the head-block with said means in a recess in the head-block, and retentively engage with said interlocking bar, and means 35 extending through said mounting and having detachable operative connection with said retentively engaging means to withdraw it from its engagement with said interlocking bar, and comprising oppositely 40 presented engaging means lying below the top of said mounting, one or the other of said engaging means being adapted to engage with a part of one or the other latch of a switch stand, accordingly as said 45 switch-lock is associated with one or the other of said latches, and being thereby adapted to hold said latch out of position for locking while said retentively engaging means is withdrawn from said engagement.

50 16. An automatic safety switch-lock comprising a housing to be supported upon and extend down into a recess in a head-block, an interlocking bar along said head-block, means in the part of the housing below the 55 top of the head-block to retentively engage with said interlocking bar, and a bell-crank comprising a transverse shaft journaled in the upper part of said housing, an arm extending down from said shaft inside the 60 housing, and operatively engaging with said retentively engaging means, and another arm extending from said shaft outside the housing to engage with part of a switch stand latch when depressed, and thereby hold said latch out of 65 position for locking while said means is withdrawn from said engagement.

while said means is withdrawn from said engagement.

17. An automatic safety switch-lock comprising a housing to be supported upon and extend down into a recess in a head-block, 70 an interlocking bar along said head-block, means in the part of the housing below the top of the head-block to retentively engage with said interlocking bar, and a bell-crank comprising a transverse shaft journaled in 75 the upper part of said housing, an arm extending down from said shaft inside the housing, and operatively engaging with said retentively engaging means, and another arm extending from said shaft outside the 80 housing and below the top of said housing, to engage with part of a switch stand latch when depressed, and thereby hold said latch out of position for locking while said means is withdrawn from said engagement. 85

18. An automatic safety switch-lock comprising a housing to be supported upon and extend down into a recess in a head-block, an interlocking bar with an opening through it along said head-block, means in the part 90 of the housing below the top of the head-block to retentively engage in said opening through said interlocking bar, and a bell-crank comprising a transverse shaft journaled in the upper part of said housing, an 95 arm extending down from said shaft inside the housing, and making detachable operative connection with said retentively engaging means, and another arm extending from said shaft outside the housing to engage 100 with part of a switch stand latch when depressed, and thereby hold said latch out of position for locking while said means is withdrawn from said engagement.

19. An automatic safety switch-lock comprising a housing to be supported upon and extend down into a recess in a head-block, an interlocking bar with an opening through it along said head-block, means in the part of the housing below the top of 110 the head-block to retentively engage in said opening through said interlocking bar, and a bell-crank comprising a transverse shaft journaled in the upper part of said housing, an arm extending down from said shaft inside the housing, and making detachable operative connection with said retentively engaging means, and another arm extending from said shaft outside the housing and below the top of said housing, to engage 115 with part of a switch stand latch when depressed, and thereby hold said latch out of position for locking while said means is withdrawn from said engagement.

20. An automatic safety switch-lock comprising a housing to be supported upon and extend down into a recess in a head-block, an interlocking bar along said head-block, means in the part of the housing below the top of the head-block to retentively engage 120

with said interlocking bar, and a bell-crank comprising a transverse shaft journaled in the upper part of said housing, an arm projecting down from said shaft inside said housing, and operatively engaging with said retentively engaging means, and arms on said shaft outside said housing at opposite sides thereof, one or the other of said arms being adapted to engage with part of one or the other latch of a switch stand, accordingly as said switch-lock is associated with one or the other latch of the switch stand, and being thereby adapted to hold the latch out of position for locking while said means is withdrawn from the engagement with said interlocking bar, and the other arm, in either instance, being readily accessible for operation of the lock and latch.

21. An automatic safety switch-lock comprising a housing to be supported upon and extend down into a recess in a head-block an interlocking bar along said head-block, means in the part of the housing below the top of the head-block to retentively engage with said interlocking bar, and a bell-crank comprising a transverse shaft journaled in the upper part of said housing, an arm projecting down from said shaft inside said housing, operatively engaging with said retentively engaging means, and arms on said shaft outside said housing at opposite sides thereof, below the top of the housing, one or the other of said arms being adapted to engage with part of a switch stand latch, accordingly as said switch-lock is associated with one or the other latch of the switch stand, and being thereby adapted to hold the latch out of position for locking while said means is withdrawn from the engagement with said interlocking bar, and the other arm, in either instance, being readily accessible for operation of the lock and latch.

22. An automatic safety switch-lock comprising a housing, a plate on the upper side of which said housing is supported, adapted to be fixed to the top of and over a recess in a head-block, a guide extending down from the lower side of said plate, an interlocking bar guided in said guide opposite to the recess in the head-block, a plunger sliding in said guide at an angle to said interlocking bar which has an opening in which said

plunger retentively engages, a spring bearing against said plunger to hold it in said engagement in said interlocking bar, a rack fixed to said plunger near said interlocking bar and having a slot presented upwardly above said plunger, and a bell-crank comprising a transverse shaft journaled in the upper part of said housing, an arm extending down from said shaft inside the housing, and engaging in said slot in said rack, another arm extending from said shaft outside the housing to engage with part of a switch stand latch when depressed, and thereby hold said latch out of position for locking while said plunger is withdrawn from said engagement.

23. An automatic safety switch-lock comprising a housing, a plate on the upper side of which said housing is supported, adapted to be fixed to the top of and over a recess in the head-block, a guide extending down from the lower side of said plate, an interlocking bar guided in said guide opposite the recess in the head-block, a plunger sliding in said guide at an angle to said interlocking bar which has an opening in which said plunger retentively engages, a spring bearing against said plunger to hold it in said engagement in said interlocking bar, a rack fixed to said plunger near said interlocking bar and having a slot presented upwardly above said plunger, and a bell-crank comprising a transverse shaft journaled in the upper part of said housing, an arm projecting down from said shaft inside said housing, and engaging in said slot in said rack, and arms on said shaft outside said housing at opposite sides thereof, one or the other of said arms being adapted to engage with part of one or the other latch of a switch stand, accordingly as said switch-lock is associated with one or the other of said latches, and being thereby adapted to hold said latch out of position for locking while said plunger is withdrawn from the engagement with said interlocking bar, and the other arm, in either instance, being accessible for operation of the lock and latch.
